UNITED STATES PATENT OFFICE

CALVIN CAMPBELL, OF DENVER, COLORADO, ASSIGNEE TO THE COLORADO FUEL AND IRON COMPANY, OF DENVER, COLORADO, A CORPORATION OF COLORADO

EXTENSION CLIP

Application filed December 10, 1928. Serial No. 324,961.

This invention relates to new and useful improvements in fastenings for composition boards, of the type shown and described in my application for Patent Serial No. 252,532 filed on the seventh day of February, A. D. 1928.

Fastenings of the type above referred to are particularly adapted for fastening wall or ceiling boards to metal studs, joists and other structural supports, and they are designed to fasten edge-to-edge adjoining boards at a definite distance from an edge of the support or/and to secure boards lying flush with an edge of the support.

In the use of fastenings of the construction disclosed in the aforementioned application for patent, it was necessary to supply fastenings of different proportions to accommodate joists or other supports of different widths and it is the object of the present invention to provide a fastening that may be adjusted to supports of different widths through the medium of a detachable link associated with one or two of the members of the fastening in which its distinctive features are embodied.

Further objects of the invention reside in details of construction and novel arrangements of parts as will fully appear in the course of the following description.

In the accompanying drawings,

Figure 1 represents a perspective view of the improved clip;

Figure 2, a perspective view of a connecting link included in the improved fastening;

Figure 3, a perspective view of a link of modified construction;

Figure 4, a perspective view of an end-member of the fastening and the adjoining portion of a link of the construction shown in Figure 3;

Figure 5, a sectional elevation showing the application of the fastening to a flanged metal support and to wall or ceiling boards meeting one another at a distance from an edge of the support;

Figure 6, a view similar to Figure 5, showing the fastening applied to a ceiling or wall board flush with a face of the flanged support;

Figure 7, a sectional elevation showing a

modified method of applying the clip to secure ceiling or wall boards disposed at only one side of a flanged joist;

Figure 8, a face-view of the construction shown in Figure 7;

Figure 9, a perspective view of the link member of the clip shown in Figures 7 and 8;

Figure 10, a sectional elevation illustrating the use of the clip in connection with a joist of angle-section;

Figure 11, a face-view of the construction shown in Figure 10; and

Figure 12, a sectional elevation showing a clip of modified construction in connection with a joist of angle-section.

Like characters of reference designate corresponding parts throughout the views.

The fastening which is of the nature of a bendable clip, consists in the construction illustrated in Figure 1, of two end members 5 and an interposed connecting link-member 6.

Each of the end members comprises two plates 7 and 8, bent at right angles to each other. The plate 8 has a yoke 9 and a flange 10, formed by a U-shaped cut, the yoke being composed of two parallel arms 9a and a connecting cross piece 9c at the end of the plate, and the flange being bent outwardly from the yoke at substantially right angles thereto.

The plate 7 has a U-shaped cut 21 forming a yoke 13 and a flange 12 which may be bent at right angles to the yoke 13 in the plane of the plate 8. The yoke has a cross-piece 13a at the end of the plate 7 for the application of a link hereinafter to be described.

The flange 10 is split as at 14, to provide tongues 15 which in practice are bent along a line 16 that may be defined by perforations or other weakening means, and the flange 12 has a similar row of perforations 17 defining a tongue 18.

In the construction disclosed in the above mentioned application for patent, the two members were integrally connected by a body member of which the plates 7 of the new construction were integral parts and the clips

could therefore be applied only to supports whose width corresponded to the length of the body member.

In the present invention the distance between the parallel plates 8 of the fastening may be varied by the provision of a detachable connecting link.

In the construction illustrated in Figure 1, the connecting link consists of a strap 19 of bendable metal, the ends 20 of which are bent at right angles to the body portion, to engage across the cross pieces 13a of the yokes 13, of the plates 7 of the end members.

After the ends of the link have been inserted in the openings of the yokes, as shown, they are bent around the cross pieces of the same upon the surface of the plate, as shown in Figures 5 and 6.

Figures 3 and 4 show as a variation of the link construction, a link composed of a strap 22 provided with T-heads 23. The width of the heads is slightly less than the length of the openings in which they are to be inserted, and the link is applied by first passing its heads through the openings of the plates of the end members of the clip, and then turning the link through an angle of 90 degrees whereby to position the heads in contact with the cross pieces of the yokes 13, as shown.

It will be apparent that in the construction illustrated in Figure 1, the distance between the end members of the clip may be varied by bending the link at different distances from its ends and that in both illustrated forms of the invention the distance between the end members may be adjusted by the provision of links of different lengths.

The method of using the clip illustrated in Figure 1 has been shown in Figures 5 and 6, in which the reference character 25 designates a joist, stud or other structural support made of flanged metal, and 24 the wall or ceiling boards fastened to the support by means of clips of the present construction.

The support has been shown as made of channel section and in Figure 5 the boards have been shown as meeting at a distance from an edge of the support.

The plates 7 of the end-members of the clip, connected by the link 6, lie flat against the body-plate 25 of the support, the plates 8 lie flat upon the flanges 26 of the support and the yokes 9 are bent around the edges of the flanges.

The flanges 10 of the end-members extend outwardly from the flanges of the support and at right angles thereto, and after the boards 24 have been placed against the flanges 26 at opposite sides thereof, the tongues 15 of the flanges 10 are bent upon the outer surfaces of the boards to secure them in place. The weakened bending lines of the flanges are at a distance from the plates of which the

flanges are a part, slightly less than the average thickness of wall or ceiling boards so that when the tongues are bent upon the boards they may be pressed into the material of which the boards are composed so as to lie flush with the outer surfaces of the same. Thus the clips may be completely concealed by a filler or filler-strips used in finishing the structure of which the boards are a part. The application of the tongues in this manner furthermore draws the boards tightly against the flanges of the support, and firmly secures the boards to the support and in mutual alignment.

The flanges 12 of the clip extending in the planes of the respective plates 8, provide an additional support for the boards at one side of the joist.

In the method of application illustrated in Figure 6; the wall or ceiling boards 24 extend to an edge of the surfaces of the support, against which they rest as frequently occurs in places where an adjoining board 27 lies flush against the face of the body plate of the support.

In this case, the flanges 10 of the clip are bent into the planes of the yokes 9 and the flanges 12 are bent at right angles to the plate 8 of which the yokes are a part, to engage with the adjoining edges of the boards. The tongues 18 of the flanges 12 are bent upon the outer surfaces of the boards 24 and the latter are thereby fastened in place, as before.

It will be apparent that the clips or fastenings may be employed at the will of the user, to fasten wall or ceiling boards in different positions relative to the joists or studs against which they are placed, by the provision of the two flanges on each end-member, which by their tongues are adapted to embrace the edges of the boards as shown and described.

The clips may be made of any suitable bendable metal and they may, if necessary, be coated with a rust-proof material.

In certain instances, the clip may be composed in its entirety of one member of the construction of the end-members of the first described construction, and a link-member of suitable length.

Referring to Figures 7 and 8 of the drawings, a clip of this character has been shown as applied to fasten ceiling boards 24 disposed at one side only of a joist 25 of angle-section. A link 28 similar to the link 19 but of greater length, is bent around the flange 20 of the joist opposite to that engaged by the ceiling boards. The opposite end of the link is hooked across the cross piece 13a of the plate 7 of a member 5 similar to the end-members hereinbefore described, and the yoke 9 of the member is bent around the other flange of the joist.

The tongues 15 of the flange 10 are pressed into engagement with the outer surfaces of the ceiling boards 24 as before, and the flange 13a

12 lies flat against the opposite surface of one of the boards. This method of application is of particular value for fastening ceiling boards that are disposed at one side of the joists only.

5 It is preferred to bend one end of the link or strap 28 before application, as shown in Figure 9, and to bend the other end of the same around the flange of the joist at the required distance.

10 In Figures 10 and 11, has been shown the method of fastening wall boards to a joist 29 of angle section.

The link 28 bent across the two sides of the angle-joist are hooked around the cross pieces 9c and 13a of the yokes 9 and 13 of the member 5. The tongues 15 of the flange 10 disposed between the wall boards, are bent in opposite directions upon the outer faces of the same and the flange 12 extends along the opposite side of one of the boards.

15 Figure 12 illustrates a modification of the clip in connection with a joist of angle-section, the parts of the clip being similar to those of Figures 10 and 11.

20 The link 28 is bent across an edge of the joist and the member 5 is bent at one end across the opposite edge of the same and extends across one side of the joist and partially across the other side of the same where it connects with the link.

25 The end of the link is, as before, bent across the cross piece 13a of the member.

It is to be noted that the U-shaped cut and 30 the flange bent outwardly therefrom have been omitted at one end of the member as being unessential.

What I claim and desire to secure by Letters Patent is:

40 1. A clip for fastening wall- or ceiling boards, comprising end-members having integral means for securing wall- or ceiling boards to a support against which they are placed, and a link-member connecting the 45 end-members.

2. A clip for fastening wall- or ceiling boards, comprising end-members having bendable parts to embrace a structural support and having means to fasten a wall- or 50 ceiling-board placed against the support, and a link-member connecting the end-members.

3. A clip for fastening wall- or ceiling boards, comprising a member having an apertured end part and integral means for securing a wall- or ceiling-board to a support against which it is placed, and a bendable strap inserted in the aperture of the part.

4. A clip for fastening wall- or ceiling boards, comprising members each having an 60 apertured end part and means for securing a wall- or ceiling-board to a support against which it is placed, and a connecting link-member having its ends inserted in the apertures of the end-parts, in abutment with an 65 edge thereof.

5. A clip for fastening wall- or ceiling-boards, comprising members each having an apertured end-part and means for securing a wall- or ceiling-board to a support against which it is placed, and a link-member having its ends inserted through the apertures of the end-parts, and bent around an edge thereof. 70

6. A clip for fastening wall- or ceiling-boards, having an apertured end-part and integral means for securing a wall- or ceiling-board to a support against which it is placed, a flange being bent out of an opening in the member, and a strap having an end inserted in the opening and engaging with an edge 80 thereof. 75

7. A clip for fastening wall- or ceiling-boards, including members having means for securing a wall- or ceiling-board to a support against which it is placed, one of the members having an apertured end part, and a link connecting the members by being hooked in 85 said aperture.

8. A clip for fastening wall or ceiling boards comprising a member bent to embrace 90 a support and having an apertured end-part and means for holding a wall or ceiling board, and a bendable strap hooked in the aperture of the part and adapted to hold the member to the support. 95

In testimony whereof I have affixed my signature.

CALVIN CAMPBELL.
